CLAIM

The ornamental design for a symbolic inner compass, as shown and described.

DESCRIPTION

FIG. 1 is a perspective view of a symbolic inner compass, showing my new design;

FIG. 2 is a front elevational view of the invention; the rear elevational view, left-side elevational view and right-side elevational view all being a mirror image thereof;

FIG. 3 is a top plan view of the invention; and,

FIG. 4 is a bottom view of the invention.
